UNITED STATES PATENT OFFICE

GEORGE E. COUTANT, OF DECATUR, ILLINOIS

CAR CONSTRUCTION

Application filed December 5, 1928. Serial No. 323,807.

This invention relates to improvements in car construction.

One object of the invention is to provide simple and efficient means for supporting the buffer platform and diaphragm face plate of railway cars, whereby the parts will accommodate themselves to the required movement with respect to the car end and platform without noise and unnecessary vibrations.

Another object of the invention is to provide means for supporting the usual buffer platform and face plate from the end and platform of a vestibule car, which permits the necessary movements of the buffer platform and diaphragm face plate longitudinally and laterally of the car without binding or unnecessary vibration, thereby eliminating jarring and noise.

A more specific object of the invention is to provide supporting means for the buffer platform and vestibule diaphragm face plate of railway cars, including links or supporting arms pivoted to the end of the car and the car platform to swing in horizontal planes and pivoted to means having sliding engagement with the buffer platform and diaphragm face plate in a lateral direction, the arms being yieldingly urged outwardly to maintain the buffer platform and the diaphragm in extended position.

Other and further objects of the invention will more clearly appear from the description and claims hereinafter following.

In the drawings forming a part of this specification, Figure 1 is an end elevational view of the buffer platform and diaphragm face plate and associated parts of a railway car of the vestibule type. Figure 2 is a partial top plan view and partial horizontal sectional view at the top of the face plate shown in Figure 1. Figure 3 is a horizontal sectional view, corresponding substantially to the line 3—3 of Figure 1. Figure 4 is a vertical, sectional view, corresponding substantially to the line 4—4 of Figure 2. Figure 5 is a vertical, sectional view, corresponding substantially to the line 5—5 of Figure 3. Figure 6 is a view similar to Figure 3, partly broken away, illustrating a different embodiment of the invention. And Figure 7 is a ver-

tical, sectional view, partly broken away, corresponding substantially to the line 7—7 of Figure 6.

Referring first to the embodiment of the invention illustrated in Figures 1 to 5, inclusive, the usual platform at one end of a vestibule type of railway car is designated by 10, and 11 is a buffer stem of well known form which cooperates with the buffer platform. The buffer stem has its inward movement yieldingly resisted by the buffering mechanism proper, not shown, the same being of any well known construction. The vestibule of the car is provided with the commonly employed form of diaphragm, not shown, attached to the car end and having a diaphragm face plate.

In carrying out my invention, I employ a platform underframe structure 12, having a buffer stem opening 13, a buffer platform 14 and a diaphragm face plate 15 fixed thereto.

The diaphragm face plate 15 is of the usual construction, having a horizontal top section and vertical side sections formed integral therewith which are fixed to the buffer platform 14. The buffer platform 14 is provided with the usual pocket or seat 16 which accommodates the front end of the buffer stem 11. The platform underframe 12 comprises a casting having pockets 17—17 formed at opposite sides of the buffer stem guide opening 13. A pair of arms 18—18 are pivotally supported at their inner ends in the pockets 17, each arm being provided with a substantially cylindrical inner end portion 19 provided with an outer circular wall and an inner hub portion 20. An annular opening is thus provided between the hub portion and the wall 19, the opening being closed at the upper end by the top wall 21 of the cylindrical end portion of the arm. The hub portion 20 is provided with a vertical pivot opening 22 which receives the pivot pin 23, having the lower end seated in a ring 24 mounted in an opening in the lower wall of the corresponding pocket 17.

The pivot pin 23 is headed at the upper end, the head being disposed within a ring 25 seated in an opening in the top wall of the pocket. Wear plates 26—26 are interposed between the cylindrical end portion of each

lever 18 and the top and bottom walls of the corresponding pocket 17. A helical spring 27 is disposed within the annular opening between the hub and the outer wall of the cylindrical portion of each arm, the bottom end of the spring being anchored to the bottom wall of the pocket and the upper end being anchored to the cylindrical end portion of the lever by having the extremity of the spring disposed in an opening in the top wall of said cylindrical portion.

5 The spring is so arranged that it tends to hold the outer end of the corresponding arm away from the fixed platform of the car, the 15 spring being placed under tension when the arm is swung inwardly.

10 The outer end of each arm 18 is provided with a bifurcated portion 87 having vertically aligned pivot pin receiving openings 28 20 in the arms thereof. This end of the lever is connected to a slide 29 comprising a plate-like portion having an upstanding ear 30 provided with a pivot opening adapted to receive a pivot pin 31 extending through the 25 same and the openings 28—28 of the arms of the bifurcated portion 87. The plate-like portion 29 of the slide is connected to a relatively wider plate-like member 32 which is 30 slidingly supported in a guideway 33 composed of a plate member having inturned top and bottom edges forming the outer walls of the guideway. The plate-like guide member 33 is secured to the vertical wall of the buffer 35 platform 14 by means of bolts or any other well known securing elements. It will be evident the slide is thus mounted for transverse movement with respect to the buffer platform in a substantially horizontal path.

35 As most clearly shown in Figure 3, the arms 40 18 of the two supporting links normally diverge laterally outwardly and are held in their extended position by the springs 27. When in this position, the buffer stem 11 is also in bearing engagement with the end wall 45 of the pocket 16 on the buffer platform. As shown in the drawings, a wear plate is preferably interposed between the front end of the buffer stem 11 and the inner wall of the pocket.

50 The diaphragm face plate 15 is provided with a guide member 34 at the top edge thereof, the guide member being in the form of a plate secured to the inner side of the diaphragm face plate by means of bolts. 55 The plate forming the guide member 34 has the top and bottom edge portions thereof bent inwardly and downwardly at their extremities to provide top and bottom guide flanges 35—35 spaced from the main body 60 portion of the plate.

65 A slide 36 is mounted within the guide member 34 and is composed of a pair of plates 37 and 38, the plate 37 having laterally extending top and bottom flanges overhanging the top and bottom edges of the plate 38.

The plate 38 is provided with top and bottom laterally extending lugs 39—39 provided with aligned pivot pin-receiving openings.

70 A pair of supporting links or arms 40—40 are secured to the end structure of the car at the top thereof by means of U-shaped bracket members 41—41. Each bracket member 41 comprises a vertically disposed plate-like section secured to the end portion of the car by rivets or any suitable securing means, and 75 top and bottom horizontally extending portions provided with aligned pivot pin-receiving openings. The inner end of each arm 40 is provided with a cylindrical pivot pin-receiving portion 42 adapted to accommodate 80 a coiled spring 43. The portion 42 is pivotally connected to the corresponding bracket 41 by means of a vertically disposed pivot pin 44 extending through the top wall of the cylindrical pivotal portion of the arm 85 40 and the aligned openings in the top and bottom sections of the bracket. One end portion of the coiled spring 43 is secured in an opening of the top wall of the cylindrical portion 42 and the other end is fixed to the 90 bottom section of the bracket, as most clearly shown in Figure 4.

95 At the outer end, each arm 40 is provided with an opening having a bushing 45 mounted therein adapted to form a bearing for a pivot pin 46 extending through the same and the lugs 39 of the slide 36.

100 As will be evident, the springs 43 maintain the arms 40 yieldingly in the position shown in Figure 2 and the parts are so proportioned that when these arms and the arms 18 which support the buffer platform are in their outermost position the diaphragm face plate 15 will be disposed in a substantially vertical plane. The pivotal supports for 105 the arms 18 and 40 are so disposed that the arms will always swing in horizontal planes, thereby maintaining the buffer platform and the diaphragm face plate at a substantially constant elevation.

110 When two cars are coupled together and the buffer platforms 14 thereof are brought into abutment, the buffer platform and the attached diaphragm face plate will be forced inwardly to a certain extent, thereby swinging the arms 18 and 40 inwardly and placing the springs under tension. During operation of the cars, when the same are subjected to draft and buffing shocks, the buffer platform, together with the diaphragm face plate of 115 each car, will be moved inwardly and outwardly with respect to the corresponding end of the car. This movement will be opposed during buff by the buffing mechanism connected with the buffer stem 11 and also by 120 the spring-pressed arms 18 and 40.

125 During the movement of the buffer platform and face plate toward the car, the arms 18 and 40 will swing on their pivots, the necessary lateral movement of the outer ends

of these arms with respect to the buffer platform and face plate being accommodated by the slides to which the outer ends of the arms are pivotally connected. The slides connected to the arms 18 will move laterally outwardly while the slides connected to the arms 40 will be moved laterally inwardly during the approach of the buffer platform and face plate toward the car end.

10 By the arrangement provided, there is no play between the parts and therefore there is no pounding or rattling. The pivotal connections of the arms provide for an easy swinging movement of the same and the slides accommodate the necessary lateral movement of the outer ends of the arms without appreciable binding effect, thereby practically eliminating all noise during the operation of the parts. As will be evident, the arrangement of supporting levers and other connections provides, in addition to the inward approach of the buffer platform and diaphragm face plate, the necessary angular movement of these parts when the cars are operated over curved track.

Referring next to the embodiment of the invention illustrated in Figures 6 and 7, 50 indicates the usual platform at the end of the vestibule type of railway cars, and 51 is a buffer stem which cooperates with the buffer platform and is slidable in an opening in the casting forming the underframe of the platform.

Inward movement of the buffer stem 51 is resisted by the usual buffering mechanism proper, not shown. The buffer platform, which is indicated by 52, is supported by a pair of pivoted arms 53—53 which are connected by vertical pivots 54—54 to the underframe of the platform structure. As shown in Figure 7, the end portion of the underframe is provided with top and bottom walls connected by a vertical end wall, and the pivot pins 54 extend through said top and bottom walls being mounted in bearing rings 55—55 disposed in openings in said top and bottom walls. The inner end of each arm 53 is forked, as shown in Figure 7, and the arms of the fork engage above and below the end portion of the platform underframe structure. The bottom end of each pivot pin 54 is disposed in a bushing or ring 56 mounted in an opening in the bottom arm of the fork and the head of the pin is mounted in a similar ring 57 disposed in an opening in the top arm of said fork. At the outer end, each arm 53 is pivotally connected to a slide 58 in all respects similar to the slide 32 described in connection with Figures 1 to 5, inclusive, the outer end of each arm being forked and the slide being provided with a lug and a pivot pin extending through the arms of the fork and the lug. The slide 58 is mounted in a guideway 59 similar to the guide member shown in connection with the

embodiment in Figures 1 to 5, inclusive. Inward movement of the arms 53 on their pivots is resisted by spring means, one of said spring means being shown at the left-hand side of Figure 6 associated with the corresponding arm 53. This means comprises a helical spring 60 having the inner end seated in a pocket 61 formed on the underframe casting. A spring follower 62 is also pivoted on the pin which connects the outer end of the arm 53 to the slide 58, the lug on the slide being bifurcated and the spring follower being provided with a pivot lug 63 which is disposed between the top and bottom members of said bifurcated lug. The spring follower bears directly on the outer end of the spring 60 and has a cylindrical stem 64 extending into the spring to keep the parts aligned.

It will be understood that the buffer platform 52 has the usual diaphragm face plate structure connected thereto and that any suitable supporting means is employed to connect the top portion of the diaphragm face plate to the end of the car, means similar to that shown in Figures 1 to 5, inclusive, being preferably used.

The operation of the device shown in Figures 6 and 7 is substantially the same as that of the embodiment of the invention disclosed in Figures 1 to 5, inclusive. When the cars are coupled together, the diaphragm face plates and the buffer platforms of adjacent cars are in engagement and the springs are placed under initial compression. In service, the buffer platform and the attached diaphragm face plate will partake of the necessary lateral swinging movement during operation of cars on curved track and the inward movement of the buffer platform and diaphragm face plate, due to buffering shocks and vibrations, will also be accommodated by the swinging movement of the arms 53 and the sliding movement of the outer ends of the same, the inward buffering movement of the parts being opposed by the springs 60 and the buffering stem 51.

While I have herein shown and described what I consider the preferred manner of carrying out my invention, the same is merely illustrative and I contemplate all changes and modifications that come within the scope of the claims appended hereto.

I claim:

1. In a railway car, the combination with 120 a buffer platform and a diaphragm face plate; top and bottom pairs of arms for supporting said platform and face plate; means for pivotally supporting each pair of arms on the car proper for swinging movement in reverse directions; and means pivotally connected to said top arms, having a sliding connection with the face plate, and means pivotally connected to the bottom pair of arms having sliding connection with the platform. 125 130

2. In a railway car, the combination with a buffer platform member and a diaphragm face plate member; of arms connected to the car proper for pivotal movement in horizontal planes, said arms having a sliding pivotal connection with said members.
3. In a railway car, the combination with a buffer platform member and a diaphragm face plate member; of a pair of arms supporting each member, said arms being pivotally connected to the car proper to swing in horizontal planes.
4. In a railway car, the combination with a buffer platform member and a diaphragm face plate member fixed to said platform member; of a pair of arms having sliding pivotal connection with each of said members; and means for supporting said arms from the car body proper for swinging movement in horizontal planes.
5. In a railway car, the combination with a buffer platform member and a diaphragm face plate member fixed thereto; of a pair of arms pivotally connected to means having sliding engagement with one of said members; means for supporting said arms on the car proper for movement in a horizontal plane; and means for yieldingly forcing said arms to swing away from the car body proper.
6. In a railway car, the combination with a buffering member; of a pair of arms pivoted to the car proper to swing in horizontal planes; means for yieldingly forcing said arms to swing away from the car proper; and means for connecting said arms to said member.
7. In a railway car, the combination with a buffering member; of a pair of arms for supporting said member, said arms being pivoted at their inner ends to the car proper to swing in horizontal planes; yielding means for swinging said arms outwardly; a slide pivotally connected to the outer end of each arm; and guide means on said member cooperating with each of said slides for guiding the same in a horizontal path in a plane transversely of said member.
8. In a railway car, the combination with a buffering member; of a pair of guideways on said member; a slide transversely movable on said member in a horizontal path in each guideway; supporting arms having their outer ends pivotally supported for swinging movement on said slides; means for pivotally supporting said arms at their inner ends on the car proper for movement in horizontal planes; and spring means yieldingly opposing inward swinging movement of said arms toward the car proper.
9. In a railway car, the combination with a buffering platform member and a fixed platform structure; of a pair of arms pivoted at their inner ends on said platform structure to swing in horizontal planes; means for yieldingly forcing said arms to swing out-

wardly; and means pivotally connected to the outer end of each arm, having a sliding connection with said member.

10. In a railway car, the combination with a fixed car platform member and a buffering platform member; of a pair of arms, each of said arms being pivotally supported at the inner end on said fixed platform member to swing in a horizontal plane; a coiled spring disposed about the pivotal center of each arm and having one end fixed to the arm and the other end fixed to the fixed platform member to swing said arm away from the fixed platform member; a slide connected to the outer end of each arm by a vertically disposed pivot; and guide means on the buffering platform member for each slide, guiding the same for lateral movement in a horizontal path.

In witness that I claim the foregoing I have hereunto subscribed my name this 26th day of November 1928.

GEORGE E. COUTANT.
